FINGER REST PLATE ON KNIVES

Maurice Polacsek, Brooklyn, N. Y.

Application September 9, 1937, Serial No. 162,964

2 Claims. (Cl. 30—295)

This invention relates to new and useful improvements in a finger rest plate on knives.

The invention has for an object the construction of a knife which is characterized by the fact that it has a cutting edge and a back edge and an arrangement on the back edge whereby one using the knife may rest his finger at several points along the back edge to assist in forcing the knife downwards to permit the user to cut safely with less exertion.

Still further the invention contemplates providing a back portion upon the back edge of the knife, extending transversely thereof and formed with several recessed areas for one's finger when using the knife.

Still further the invention contemplates a modification in which a finger rest plate member is slidably mounted upon the back edge of the knife and is adapted to assume various longitudinally adjusted positions for the convenience of one using the knife.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a knife constructed according to this invention.

Fig. 2 is a bottom view of Fig. 1.

Fig. 3 is a vertical sectional view taken on the line 3—3 of Fig. 1.

Fig. 4 is a similar view to Fig. 2 but illustrating another form of the invention.

Fig. 5 is a similar view to Fig. 2 but illustrating still another form of the invention.

Fig. 6 is a side elevational view of the knife constructed according to this invention, but illustrating a modified form.

Fig. 7 is a sectional view taken on the line 7—7 of Fig. 6.

The finger rest plate for knives, according to this invention, is used in conjunction with a knife 10 having a cutting edge 10^a and a back edge 10^b. A back portion 11 is formed on the back edge 10^b and extends transversely thereof and is formed with several recessed areas 11^a, 11^b and 11^c for one's finger when using the knife. In plan view the back edge of the knife is arranged to taper, as shown in Fig. 2. The recessed portions are of a curvature adapted to preferably fit one's finger tips. The knife blade 10 is supported in a knife handle 12 and the back portion 11 is arranged

longitudinally of the knife blade starting immediately adjacent the inner end portion of the handle 12.

In Fig. 4 the recessed areas 11^a, 11^b and 11^c are shown to be of curved contour.

In Fig. 5, the edges 11' of the back portion 11 are formed with symmetrical contours corresponding with the shapes of the recessed areas. In other respects this form of the invention is similar to that illustrated in Fig. 4.

In Figs. 6 and 7 another embodiment of the invention has been disclosed in which a knife blade 14 is illustrated supported on a handle 15. This blade has a cutting edge 14^a and a back edge 14^b. A portion of the back edge 14^b immediately adjacent the handle 15 is formed with a pair of spaced parallel grooves 16 upon each of the faces thereof. A finger rest plate member 17 has a pair of resilient side walls 17^a, and is slidably mounted on the back edge 14^b of the knife blade. These walls 17^a have projecting portions 17^{aa} engaging into the grooves 16.

The outer end of the finger rest plate 17 is formed with a recessed curved surface 18 adapted to fit one's finger tips. The back edge 14^b of the blade is formed with serrations 19 along the area in which the finger rest plate member 17 may be adjusted. These serrations 19 are engageable with complementary serrations 19' formed on the inner face of the finger rest plate member 17.

Normally, the projections 17^{aa} engage the foremost grooves 16. In this position the finger rest plate member 18 is fixed and cannot be moved. In order to adjust the same it is necessary that it first be pulled outwards to the dot and dash line position 17' in Fig. 5. In this latter position the projections 17^{aa} engage the back groove 16, and the serrations 19 are disengaged from the complementary serrations on the finger rest plate member. The finger rest plate member may now be moved forwards and rearwards to any desired position. When it is pressed inwards so that the projections 17^{aa} reengage the front grooves 16 it will be held in its new position.

It is to be understood that this invention may be applied to knives of all types, such as kitchen knives, pocket knives, knives used as curving tools, etc.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is—

- 5 1. In a device of the class described, a flat member having a pair of parallel grooves formed in both faces thereof and spaced in from one edge of said member, a U-shaped element engageable over the edge of said member adjacent said grooves, cooperative serrations formed upon the 10 edge of said member and the adjacent face of said element for holding said element fixed upon said member, and an inwardly extending projection formed on each of the arms of said element and said projections being engageable into the innermost grooves of said pairs of grooves for holding said element in a position in which said serrations will be inter-engaged.
- 15 2. In a device of the class described, a flat member having a pair of parallel grooves formed in both faces thereof and spaced in from one edge 20

of said member, a U-shaped element engageable over the edge of said member adjacent said grooves, cooperative serrations formed upon the edge of said member and the adjacent face of said element for holding said element fixed upon said member, and an inwardly extending projection formed on each of the arms of said element and said projections being engageable into the innermost grooves of said pairs of grooves for holding said element in a position in which said serrations will be inter-engaged, said arms of said U-shaped element being resilient to permit said element to be manually pulled outwards to engage said projections into the outermost grooves of said pair of grooves to disengage said serrations to free said element so that it may be moved to various adjusted positions along the length of said grooves. 5 10 15

MAURICE POLACSEK.
